(57) **CLAIM**

We claim the ornamental design for a dish washer, as shown.

DESCRIPTION

FIG. 1 is a top, front, and left side perspective view of a dish washer showing our new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof; and,

FIG. 8 is a top, front, and left side perspective view of the dish washer of FIG. 1 shown with a front door in an open position and exposing a control panel on a top edge of the door.
